FUEL TREATING DEVICE

William M. Malouf, Los Angeles, Calif., assignor
to M-M & M Engineering and Research Corporation, Inc.

Application May 24, 1948, Serial No. 28,941

18 Claims. (Cl. 48—180)

1

This invention relates to improvements in fluid mixing, atomizing, and homogenizing devices, and particularly to carburetting devices.

In one of its aspects this invention is an improvement upon the inventions of Patents Nos. 1,806,356; 1,806,404; and 1,806,406. These patents describe the action of freely suspended rotating members, rotated by the stream of air or fluid to atomize the stream and to thoroughly mix the stream.

One of the preferred embodiments, more particularly illustrated in Fig. 4 of Patent No. 1,806,406, comprises a ball having peripheral recesses acting as vanes which are connected by cross or chordal bores. The fluid stream, if of sufficient velocity, causes the ball to float on the stream, and the impingement of air on the vanes causes the ball to rotate at a high speed.

While such structures are highly efficient, I have observed a phenomenon which permits me to vary the design of the ball in order to obtain an increase in its efficiency and to permit a novel application thereof.

I have observed that when the ball spins in the fluid stream there is a region of high pressure at the surface of the ball at or near, i. e., contiguous to, the plane perpendicular to the axis of rotation of the ball and a region of low pressure at or near the axis of rotation of the ball.

I have found that by connecting the cross, i. e., chordal, bore connected to the peripheral recess acting as vane with a diametric bore, the ball orients itself so that the diametric bore is substantially perpendicular to the direction of the fluid stream and the impingement of the air on the vane causes the ball to rotate. Apparently, the region of low pressure at the diametric bore of the rotating ball in conjunction with the region of high pressure at the surface of the ball adjacent the vane causes a pumping action to occur. The action of the stream of fluid indicates that it is sucked into the diametric bore and expelled through the chordal bore due to centrifugal action. The resultant action causes a local shearing of the fluid stream at or near the rotating ball surface and an impingement of the expelled stream from the ball which additionally reacts against the stream. This action causes a rotation of the stream at or near the ball and a region of extremely high turbulence in the conduit in which the ball is positioned. This action causes an extremely fine atomization of any fluid, such as fuel or other liquid, suspended in the air or other gases passing by the ball. I have been able to atomize heavy fluid such as diesel oil in air, as well as lighter fluids such as gasoline and kerosene.

It is generally recognized that the efficiency of the combustion of liquid fuel is dependent upon the degree of atomization of the fuel. The finer

10

the degree of dispersion of the liquid fuel in the air stream the more efficient the combustion.

In internal combustion spark ignition engines there is a segregation of heavy and light ends of the gasoline in the air stream passing to the several cylinders due to inefficiency of the fuel distribution of the intake manifolds. This is because there is a partial distillation of the gasoline from the relatively large droplets of the fuel in the air stream.

15

The carburetted air stream is composed of liquid particles, vapor, and air and at bends in the distributor system, and also as the stream progresses the inertia of the relatively heavy liquid fuel particles and gravity acting thereon causes a segregation of the fuel and the end cylinders may get a reduced amount of liquid fuel and a greater amount of vapor and air. Additionally, since the light ends of the gasoline are vaporized, the cylinders are not only fed with different ratios of air to fuel, but the fuel is not of uniform composition.

20

It is well known also that this effect is worse at low speed than at high speed in the spark ignition engine.

In my device, I find that the degree of atomization is so fine that an aerosol is established and there is no segregation of the fuel. Each cylinder can therefore be fed with the same mixture.

While I find one of the greatest utilities of my invention is in carburetting fuel, it also may be applied to any purpose where a liquid is to be atomized in a gas stream or where gases are to be mixed.

These and other objects of my invention will be further described in connection with one preferred embodiment of my invention illustrated in the drawing, in which

Fig. 1 is a view partly in plan and partly in section of the application of one form of my invention to the carburetor of a spark ignition engine;

Fig. 2 is a plan view of my device positioned in the gasket used in Fig. 1;

Fig. 3 is a view partly in section taken on the line 3—3 of Fig. 2;

Fig. 4 is a view partly in section, similar to Fig. 3, of a different form of my invention;

Fig. 5 is a view partly in section, similar to Fig. 1, but of a different form of my invention;

Fig. 6 is a plan view of the rotating ball of my invention;

Fig. 7 is a view taken on the line 7—7 of Fig. 6; and

Fig. 8 is a view partly in section of the application of the ball of Fig. 6 to a mixing nozzle.

The ball 1 shown in Figs. 6 and 7 contains a diametric bore 2. At the surface of the ball is an angularly disposed vane formed by milling the ball so that the cup-shaped recess 3 acting as a

2

vane is so disposed that the axis 4 of the cup-shaped vane 3 is upon a chord of the sphere. It will be observed that the intersection of the plane passing through the axis 4 and perpendicular to the axis of the diametric bore 2, i. e., the section shown in Fig. 7, shows a scoop-shaped surface at 5 and a steeper curved section at 6. Through the section 6 is passed a drill to cut a chordal bore 7 whose axis 8 intersects the axis 4. The bore 7 is of such diameter that it intersects the bore 2 at 9 so that there is a fluid passage from bore 2 through 9 into the bore 7. The forward end of the bore 7 does not extend through the periphery of the ball but terminates at 10 inside the ball. I may employ only one of such bores 7 and one of such vanes 3, but I may also position one vane at each end of the bore; for example, I may omit bores 7' and 7'' and retain 7 and employ vane 3 alone or vane 3 and vane 3'.

While I may use only one of such vanes 3 and bores 7 in conjunction with the diametric bore 9, I find that a plurality thereof are most efficient for my purpose. In employing a plurality thereof I position the several chordal bores so that they will all intersect each other at the vanes and will all intersect the diametric bore. There is therefore a communication between all of the vanes and between the vanes, chordal bores, and the diametric bore.

If I employ more than two vanes, I may position them so that I may form two bores similar to 7, each of which will terminate at an end such as 10 inside the ball for purposes to be more fully described below.

When I employ three such vanes and three such bores I prefer to make the chordal bores coplanar. This is not entirely essential, as will be clear from this disclosure, but is, however, preferable. While the plane of the chordal bore axis may intersect the diametric bore at an acute angle, I have found the most practical result to be if the plane is perpendicular to the diametric bore. This form is illustrated in Figs. 6 and 7.

The axes 8, 8' and 8'' of the diametric bores 7, 7', and 7'' are all coplanar and intersect each other at equal angles. As shown, this forms an isosceles triangle. The vanes 3, 3', and 3'' are similarly positioned with respect to the bores 7, 7', and 7'' and their respective axes 8, 8', and 8''.

The vanes 3' and 3'' have also the surfaces 5', 5'', and 6' and 6'' similar to 5 and 6 of vane 3. Each of the bores 7' and 7'' terminates at 10' and 10'' in a manner similar to 10 of bore 7, and each of the chordal bores 7' and 7'' intersect the diametric bore at 9' and 9'' similarly to the intersection 9 of the bore 7 with the diametric bore 2.

It therefore will be seen that the chordal bore 7 intersects the bore 7' and projects through the surface of the bore 7' to form a notch or ledge 10 at the entrance of the vane 3', and similarly the bore 7' intersects the bore 7'' and projects through the surface thereof to form a notch or ledge 10' at or near the entrance of the vane 3''. Also, in like manner, the bore 7'' intersects the bore 7 and projects through the wall thereof to form a notch or ledge 10'' at or near the entrance of the vane 3.

While I do not wish to be bound by any theory of the action of my device, I believe that its properties may be explained by the following.

When the air stream passing in either direction, i. e., is in either the direction of the arrow A or at 180° thereto, the ball, irrespective of

its initial position, orients, as indicated in Fig. 6, with the axis of the bore 2 substantially perpendicular to the direction of the air stream as indicated by the arrow A. The air stream enters, for example, through 3 and passes down the chordal bores 7 and 7''. The air stream in 7 impinges on ledge 10 and exits through 3'. There is thus a reactive thrust against 6' and 10. In like manner the air stream in 7'' exits through 3'' and there is thus a reactive thrust at 3' and 3'' which establishes a couple. In like manner the air stream entering the vane 5 creates a thrust against the leading edge 6 and a three-way couple is thus established which causes rotation and a clockwise rotation is established. Of course, when the ball has rotated 120° the vane 3'' is now in the place of 3 and the functions described above are repeated in sequence as the ball is rotated through 120°.

As the ball starts rotating and picks up speed as the inertia of the ball is overcome, a region of low pressure is generated at the entrance of the bore 2 and the air thus enters 2 and adds to the volume of air passing out of 3' and 3'', increasing the velocity of the ball.

Air is thus circulated from the stream of air by way of the vane in position of attack by the stream (the entrance of vane 3, Fig. 7), and by way of the diametric bore 2 and out of the vane in position of discharge (see 3' and 3'', Fig. 7). There is thus a pumping action, the ball acting as a freely suspended centrifugal rotor or jet acting pump.

If the air and fluid stream indicated by A, Figs. 6 and 7, is a mixture of a liquid and a gas, the action will cause an extremely fine atomization of the fluid in the air stream, i. e., an extremely fine aerosol.

Fig. 8 shows one application of this principle for such purpose. It illustrates a burner for a petroleum oil such as fuel oil or lighter oils such as burner oil, kerosene or gasoline or as an atomizer for other fluids. As illustrated it is composed of a burner or nozzle body 11 carrying a bore 12 in which there is a Venturi restriction 13. A side tube 14' carrying a bore 14 is connected at the vena contracta of the venturi. The bore 12 is fed by a valved line 15. In the discharge end of the bore 12 is threaded a nozzle tip 16 carrying a semi-spherical seat 17 into which a ball 19, such as shown in Figs. 6 and 7, is positioned. The radius of curvature of the seat 17 is the same as that of the ball 19 and the height of the seat is equal to the radius. The cap 20 is positioned on the tip 16 and carries a bore axially disposed with the axis of 12. The cap may have a spherical surface similar to that described for seat 17.

Air or steam under pressure is introduced through 15 and mixed with liquid fuel entering through 14' and the mixture passes up through 16. When a critical air velocity is established, the ball raises off its seat and orients itself with the bore 2 perpendicular to the axis of the bore in 16 and rotates at a high velocity. The coarse mixture of the fuel and vapor or air becomes an extremely fine aerosol and on ignition burns with a clear blue flame and with complete combustion. If an aerosol of other fluid is required, the fluid to be atomized is introduced through 14 and the air or gas through 15 and a fine aerosol exits through 21.

It is of interest to note that, depending upon the velocity of the air through 15, the exiting air through 21 is vibrating and a whistle occurs.

The frequency of the sonic wave depends upon the pressure in line 15 and increases as the pressure increases. As the pressure exceeds a critical limit, depending upon the constants of the nozzle, the frequency may become supersonic. Thus, a supersonic wave of high intensity and great energy may be emitted by this means and beamed by pointing the nozzle. In such case, of course, the side line 14 is not necessary and may be omitted or closed off by closing the valve 14'.

It is an interesting property of the device that the ball functions irrespective of the direction in which the nozzle is pointed. Thus, if the initial position of the nozzle is down and the ball is on the seat 29, closing 21, as pressure is turned on the nozzle, the ball will rise counter to gravity and against the direction of the fluid stream and will start rotating in the manner described. While I do not desire to be bound by the theory, I believe that the rotating ball becomes an air foil with a piling up of the air behind the ball to lift the ball against gravity and the direction of the air stream.

I have also found that this device has a great utility in carburetion in internal combustion engines. Thus, as illustrated in Fig. 5, the ball may be mounted in the fuel-air induction line of an internal combustion spark ignition engine between the fuel nozzle and preferably between the throttle and the engine intake manifold. As illustrated in Fig. 5, line 22 is the air-fuel line and 23 is the conventional throttle. Line 22 carries a flange 25. Between flange 25 and the manifold flange 26 is a gasket 27 in which are positioned two spring clips 28 diametrically opposed. These carry suspended a tubular coil spring. On the coil spring 29 is a cup 30 having a spherical seat 31 and nozzle 32. Peripheral openings 30a above the seat 31 may also be provided. In the seat 31 is positioned a ball 33 of construction similar to that shown in Figs. 6 and 7. The seat may be of substantially the same radius of curvature as the ball. It will be observed that the seat of the ball is suspended on the coil spring axially of the axis of the spring and the ball is thus positioned inside the coil spring axially thereof. The stream of air and fuel passing from the carburetor through the throttle passes up 32, causes the ball to rotate and causes an atomization of the fuel and air in the manner previously described.

Instead of the carburetor being up-flow, as indicated by the arrow, the flow of the air fuel mixture may be in a direction opposite to the arrow in Fig. 5. Notwithstanding that the initial or rest position of the ball is on the seat 31 to close the opening 32, the downflow of the air, if of sufficiently high velocity, causes the ball to rotate and rise off its seat to float in the air stream and act as an atomizer, as described above.

The support for the ball is thus spring or yieldably suspended. The seat for the ball is axially positioned in the air stream and is yieldingly supported and not rigidly connected to the conduit. Any vibration set up in the seat and cage for the ball is thus not transmitted to the walls of the conduit but is damped out before it reaches the conduit walls.

Figs. 1-3, inclusive, show a variation of the device adapted for use in a spark ignition internal combustion engine. Thus, 30' is the air induction line in which the choke 31' is positioned and in which is mounted a carburetor 32, throttle 31a, and a flange 33. A manifold 34 is flanged at 35. Between the flanges is a gasket 36. On the gasket are mounted two bent-over flat spring clips

37. At each end of the U tube 38 is mounted a tubular coil spring 39 and 43. The ends of the tube are swaged to form a bell mouth 42 and 43' on which the tube is suspended in the tubular springs. The springs are suspended on the clips. The spring 39 is fairly tightly wound while the spring 40 is wound tightly at 43 adjacent the bell mouth 42 to form a spherical seat for the ball. They are more loosely coiled at 41 and then wound in a helix of smaller diameter at 45 to form a retaining member for the ball.

The U tube is positioned so that the spring 39 is adjacent the edge of the throttle when the throttle is in part throttle or road load position, as shown in Fig. 1. When the throttle is thus in road load or in idling position the mouth opening of the tubular coil 39 is directly underneath the open edge of the throttle. The mouth 43' is thus exposed not only to the static pressure of the air stream but also to the dynamic head of the high velocity air stream issuing through the restricted opening between the throttle edge and the wall of the conduit 30'. The tube 42 is closed by the ball 44 and therefore a pressure is built up underneath the ball 44 to a total pressure equal to the dynamic head and the static pressure of the gas stream at 40. The air velocity above the ball 44 underneath the canopy of the throttle is at a lower velocity. The effect of this air stream and the stream of air passing over the ball 44 in the direction of the arrows causes the ball 44 to spin and rise off its seat 42 to spin freely in the air stream and to atomize the mixture of fuel and air.

In the form shown in Fig. 4, the U tube 46 is similarly constructed with each end formed in the fashion of the end at 42 and 43', in that each end of the U tube 46 carries a belled end 47 on which is wound a tight helix to form a spherical seat at 48, more loosely wound at 49, and formed at 50 in a helix of restricted diameter to retain the ball 51. The U tube is suspended in the same manner as the U tube 38.

When positioned as is the tube in Fig. 1, the down flowing stream in the direction of the arrow passes over the balls and causes them to spin and rise from their seats 48. Pressure is equalized underneath both balls by the U tube 46. The action is then as is described previously for the other forms.

The resilient suspension of the ball seat in the forms of Figs. 1-5, inclusive, isolates the unit from the walls of the air fuel system. Since vibratory forces of substantial dimensions may be set up at some stages of the operation of the ball, the yielding support dampens them out before they reach the walls and prevents the transmission thereof to the air fuel conduit.

While I have throughout this specification referred to the units shown in the figures as a ball, because for practical reasons this shape is to be desired, their functioning is not entirely dependent upon its spherical outer shape, as will be understood by those skilled in the art, and the rotating mass may be polygonal, ellipsoidal, or of any arbitrary outer shape, provided that the internal structure and the positioning of the vanes are preserved. Thus, the shape between the vanes 3, 3', and 3'' shown in Fig. 7 is of secondary significance. For practical purposes both as to construction and efficiency of operation I prefer to employ a spherical body. When the mass rotates it generates in space a solid of rotation. The term "ball" is intended to comprehend these other solid shapes.

While I have described a particular embodiment of my invention for the purpose of illustration, it should be understood that various modifications and adaptations thereof may be made within the spirit of the invention as set forth in the appended claims.

I claim:

1. A rotatable ball member comprising a diametric bore through said ball, a chordal bore in said ball intersecting said diametric bore, a peripheral recess acting as a vane at the surface of said ball and connected to one end of said chordal bore.

2. A rotatable ball member comprising a diametric bore through said ball, a plurality of co-planar chordal bores in said ball, each chordal bore intersecting said diametric bore, and peripheral recesses acting as vanes formed in the surface of said ball and positioned at the surface of said ball, each recess connected to a chordal bore.

3. A rotatable ball member comprising a diametric bore through said ball, a plurality of co-planar chordal bores in said ball, each chordal bore intersecting said diametric bore, and peripheral recesses acting as vanes formed in the surface of said ball and positioned at the surface of said ball, each recess connected to two of said chordal bores.

4. A rotatable ball member comprising a diametric bore through said ball, a plurality of co-planar chordal bores in said ball, each chordal bore intersecting said diametric bore, and peripheral recesses acting as vanes formed in the surface of said ball and positioned at the surface of said ball, each recess connected to two chordal bores, one of said chordal bores terminating in a notch at each of said vanes.

5. A rotatable ball member comprising a diametric bore through said ball, a plurality of co-planar chordal bores in said ball, the axes of said chordal bores forming an isosceles triangle, each chordal bore intersecting said diametric bore, and peripheral recesses acting as vanes formed in the surface of said ball and positioned at the surface of said ball, each recess connected to two chordal bores.

6. A ball member adapted for rotation about an axis in a moving air stream, comprising a diametric bore therethrough, and an additional bore therethrough terminating at the surface of said ball and communicating with said diametric bore within said ball.

7. An atomizing unit suitable for use in an air fluid mixture, comprising a U tube, a tubular coil spring at one end of said U tube, a ball containing peripheral recesses acting as vanes mounted in said tubular coil upon one end of said U tube, a second tubular coil spring mounted upon the other end of said U tube, and a spring clip mounted upon each of said tubular coils.

8. An atomizing unit suitable for use in a fluid mixing system comprising a U tube, a tubular coil spring mounted at each end of said tube, a ball carrying peripheral recesses acting as vanes positioned in each of said coils, and spring clips mounted on each of said coils.

9. A fuel atomizing carburetion system for internal combustion engines comprising an air fuel conduit, an atomizing nozzle comprising a U tube, a ball containing peripheral recesses acting as vanes mounted in said tubular coil upon one end of said U tube, a second tubular coil spring mounted upon the other end of said U

7 tube, and a spring clip mounted upon each of said tubular coils.

10. A fuel atomizing carburetion system for internal combustion engines comprising an air fuel conduit, an atomizing nozzle comprising a U tube, a tubular coil spring mounted at each end of said tube, a ball carrying peripheral recesses acting as vanes positioned on each of said coils, and spring clips mounted on each of said coils.

11. An atomizing unit suitable for use in an air fluid mixture, comprising a U tube, a tubular coil spring at one end of said U tube, a freely rotatable ball mounted in said tubular coil upon one end of said U tube, a second tubular coil spring mounted upon the other end of said U tube, and a spring clip mounted upon each of said tubular coils.

12. An atomizing unit suitable for use in a fluid mixing system comprising a U tube, a tubular coil spring mounted at each end of said tube, a freely rotatable ball positioned in each of said coils, and spring clips mounted on each of said coils.

13. A fluid atomizing device comprising a U tube, a freely rotatable ball, means for mounting said ball for free rotation at one end of said U tube, and means for positioning said U tube in a stream of fluid to be atomized.

14. A fluid atomizing device comprising a U tube, a freely rotatable ball, having peripheral recesses acting as vanes, means for mounting said freely rotatable ball at one end of said U tube, and means for positioning said U tube in a stream of fluid to be atomized.

15. An atomizing system, comprising a fluid conduit, a tubular coil spring housing resiliently suspended in said fluid conduit, a freely rotatable ball in said housing, a seat for said ball in said housing, a port in said seat, a tube connected to and forming a fluid passageway to said tubular housing, and a fluid outlet from said housing axially disposed in relation to said ball.

16. A rotatable ball member adapted for rotation in a moving air stream comprising a diametric bore through said ball, and a chordal bore in said ball intersecting said diametric bore.

17. A rotatable ball member adapted for rotation in a moving air stream comprising a diametric bore through said ball, and a plurality of chordal bores disposed in a plane, said plane being at an angle to said diametric bore and said chordal bores each intersecting said diametric bore.

18. A rotatable ball member adapted for rotation in a moving air stream comprising a diametric bore through said ball, and a plurality of chordal bores disposed in a plane, said plane being perpendicular to said diametric bore and said chordal bores each intersecting the diametric bore.
